TIRE

John T. Smith, Norton, and James W. Stiffler, Tallmadge,
Ohio, assignors to The Goodyear Tire & Rubber Com-
pany, Akron, Ohio

Filed Sept. 15, 1971, Ser. No. 180,945

Term of patent 14 years

Int. Cl. D12—15

U.S. Cl. D12—145

FIG. 1

FIG. 2

FIG. 1 is a perspective view of a tire showing one embodiment of our new design, it being understood that the full line portion of the design is repeated throughout the circumference of the tire, the opposite side being substantially the same as that shown; and

FIG. 2 is a perspective view of a modified embodiment of the tire illustrated in FIG. 1.

We claim:

The ornamental design for a tire, substantially as shown and described.
